(57) **ABSTRACT**

An apparatus in the treatment of stock passed to a headbox of a paper machine or equivalent includes at least two stock chests (10a₁, 10a₂). Stock (M₁) from a first stock chest (10a₁) is passed along a line (a₁, a₂) to a hydrocyclone plant (20) in the short circulation of the paper machine or equivalent. An accept line (a₃) of the hydrocyclone plant is connected with a stock line (b₁) of the stock (M₂) fed from a second stock chest (10a₂), and a combined stock flow is passed along a line (b₂) to the headbox (100) of the paper machine or equivalent. A method in the treatment of the stock passed to a headbox of a paper machine or equivalent is disclosed.

RESEARCH AND DEVELOPMENT**

Not applicable.

BACKGROUND OF THE INVENTION

The invention relates to an apparatus and a method in the treatment of the stock passed to a headbox of a paper machine or equivalent.

Centrifugal cleaning is needed in paper machines for separation of sand and contaminants. With today's technology, the cleaning efficiency of centrifugal cleaning deteriorates when the fiber consistency of the pulp suspension exceeds 1 percent. This limits the increasing of the feed consistency of the stock to be fed to the headbox. In practice, the slotted screen technique has made it unnecessary to use centrifugal cleaning for separating reject fibers, such as shives. A hydrocyclone plant is placed in the short circulation of the paper machine, where the flow rates are high, as high as 2000 l/s. To be operative, centrifugal cleaning requires a pressure difference of 120-150 kPa. In that connection, all (about 5) steps of the hydrocyclone plant require pumps, which represent as much as about 25 percent of the energy consumption of the short circulation. At a flow rate of 2000 l/s, the power consumption of centrifugal cleaning is about 1200 kW. A typical amount of fiber reject from centrifugal cleaning is about 0.1-0.2 percent of production. The loss of the filler pigments coming with coated broke is at its worst about 0.5 percent of machine production.

A filler recovery system is often incorporated in connection with the centrifugal cleaning of the short circulation. In addition to filler, the system must also process other rejects, such as fiber reject and sand, coming from the short circulation. In that case, the efficiency of the filler recovery system is not best possible.

Concepts are known in which the cleaning of the stock has been transferred from the short circulation to pulp lines. The consistency (about 3 percent) of the broke system is, however, not suitable for separation of sand with hydrocyclones.

When centrifugal cleaning is in the pulp line (e.g. chemical pulp, DIP or TMP), these pulps need not be cleaned again any more, but the debris, sand and non-disintegrating coating sheets of paper coming to the broke system via pulpers should be treated by means of hydrocyclones.

SUMMARY OF THE INVENTION

By placing a hydrocyclone plant in accordance with the invention in a broke system line in the short circulation, the problem is solved. The fiber consistency in the headbox can

be increased, when needed, to a level of over 2 percent without the fiber consistency in the centrifugal cleaning exceeding the limit of 1 percent.

The size and the energy consumption of the hydrocyclone plant would be only about one third of the present size and energy consumption. The size is determined based on the maximal broke percentage.

At the same time, better selectivity is achieved in the filler recovery process.

In the invention, a hydrocyclone plant is placed in a stock line which is in the short circulation and uses broke, and it is connected with another stock line, so that the bulk of the stock flow (the purer stock) bypasses centrifugal cleaning.

The proposal reduces the energy consumption of centrifugal cleaning by about 65 percent, which means a saving of about 17 percent in the energy need of the short circulation. On a large machine the saved power is about 800 kW.

The amount of reject from centrifugal cleaning is reduced to a fraction, which means that the amount of reject from centrifugal cleaning would be in its entirety less than 0.05 percent of production. In practice, it could halve the amount of reject in the area of the paper mill, thus reducing the handling capacity associated with fiber recovery.

The investment in equipment is reduced by about 65 percent in centrifugal cleaning and by about 10 percent in respect of the short circulation. A hydrocyclone plant is a subprocess that takes up much space. By means of the arrangement in accordance with the invention, the paper machine hall is shortened by 3 m, with the result that the saving in building costs is considerable.

In accordance with the invention, a system is formed that includes at least two stock chests. The first stock chest comprises a stock composition M_1 containing pulp that requires centrifugal cleaning before it is passed to the headbox of the paper machine. The stock composition M_1 contains broke pulp passed from the paper machine and, in addition, it can contain pulp coming from fiber recovery and further mechanical pulp. The second stock chest comprises a stock composition M_2 containing pulp that has already undergone centrifugal cleaning, such as recycled fiber and/or chemical pulp and/or TMP. Thus, it does not contain any broke coming from the paper machine. In the arrangement in accordance with the invention, only the stock M_1 of the first stock chest is treated in the hydrocyclone plant and at least one accept is passed from it into connection with a second stock chest line and its stock M_2 . There can be more stock chests than two.

The apparatus in accordance with the invention thus includes a hydrocyclone plant that is much cheaper in capital expenditure and takes up less space than that of the prior art because its capacity need not be as high as that of the prior art arrangements in which all stock is passed through a hydrocyclone plant. In the arrangement in accordance with the invention, it is only the stock M_1 which has come as broke that is passed through the hydrocyclone plant in the short circulation of the headbox.

In the following, the invention will be described with reference to some advantageous embodiments of the invention shown in the figures of the appended drawings, but the invention is not meant to be exclusively limited to them.

BRIEF DESCRIPTION OF THE DRAWINGS

FIG. 1A shows a prior art apparatus for passing stock to a headbox of a paper machine.

FIG. 1B shows an arrangement in accordance with the invention.

FIG. 2A shows a first embodiment of the invention in which broke-containing stock is passed from a first stock chest to a hydrocyclone plant, and in which embodiment the stock is passed through a wire pit.

FIG. 2B shows a second embodiment of the invention.

FIG. 3 is an illustration of principle of the operation of a hydrocyclone plant.

DESCRIPTION OF THE PREFERRED EMBODIMENTS

FIG. 1A shows a prior art stock system in which all stock $M_1+M_2+M_3$ is passed to a hydrocyclone plant 20, which means that a high capacity is required from the hydrocyclone plant.

FIG. 1B shows an arrangement in accordance with the invention. A stock chest 10a₁ contains stock, i.e. a pulp fraction M_1 , which contains broke passed from a paper machine and said pulp fraction M_1 is treated in a hydrocyclone plant 20. The cleaned stock, its accept is passed further into connection with stocks M_2 and M_3 that do not contain broke and further to a headbox 100. The pulp fractions M_2 and M_3 that do not contain broke in stock chests 10a₂ and 10a₃ thus bypass the centrifugal cleaning 20, and the accept of the stock M_1 from the hydrocyclone plant 20 is passed into connection with said stocks M_2 and M_3 . The hydrocyclone plant 20 is not required to have as high a capacity as that of the embodiment of FIG. 1A.

In the embodiment of FIG. 2A, stock M_1 , or a pulp fraction, of a first stock chest 10a₁ also comprises a stock composition that requires centrifugal cleaning before it is passed to a headbox of a paper machine. The stock M_1 contains broke coming from the paper machine and, in addition, it may contain pulp coming from fiber recovery, and further mechanical pulp.

Stock M_2 of a second stock chest 10a₂ comprises a stock composition that has already undergone centrifugal cleaning, such as recycled fiber and/or chemical pulp and/or TMP.

In the embodiment of FIG. 2A, the stock M_1 is passed from the stock chest 10a₁ through a stock line a₁ to a lower part of a wire pit 11. The line a₁ includes a pump P₁. In the lower part of the wire pit, the stock M_1 is diluted with wire water obtained from a wire section of a paper machine (not shown) along a line d₁ to a consistency required by a hydrocyclone plant 20. A line a₂ leads from the lower part of the wire pit 11 to the suction side of a pump P₂ and a line a₂ leads from the pressure side of the pump P₂ to a first centrifugal cleaning step 20a₁ of the hydrocyclone plant 20 situated in the short circulation of the paper machine. In the figure, the centrifugal cleaning steps are designated with 20a₁, 20a₂, 20a₃ . . . An accept line from the centrifugal cleaning step 20a₁ of the hydrocyclone plant 20; a line a₃ is passed further to join a line b₁ of the stock M_2 of the second stock chest 10a₂ via a mixing device 12. The mixing device 12 is also supplied with wire water from the wire pit 11 along a line e₁ for diluting the stock M_2 to be fed to the headbox 100 to a suitable consistency.

From the upper part of the wire pit 11 there is further a line c₁ for dilution water, said line c₁ including a pump P₃. The line c₁ leads further from the discharge side of the pump P₃ to a deaeration tank 13a₁. The dilution water passed through the deaeration tank 13a₁ is conducted further after the deaeration treatment to a discharge line f₁ and further while pumped by a pump P₄ to a machine screen 14a₁, whose accepted fraction, i.e. accept, is passed to a dilution inlet header J₂ in the headbox 100.

The stock chest 10a₂ is provided with the line b₁ for the stock and further to the suction side of a pump P₅. On the

discharge side of the pump P₅, the line b₁ is connected to the mixing device 12, after which there is a pump P₆ in a line b₂ for pumping the combined stock further along the line b₂ to a deaeration tank 13a₂, from which a discharge line f₂ leads further to the suction side of a pump P₇. On the discharge side of the pump P₇, in the line f₂, there is a machine screen 14a₂, from which an accepted fraction, i.e. accept, is passed to a stock inlet header J₁ of the headbox 100.

In the device arrangement in accordance with the invention, only the broke-containing stock M₁ passed from the stock chest 10a₁ is treated in the hydrocyclone plant 20. An accept line a₃ leads from said hydrocyclone plant further into connection with the stock line b₁ of the stock M₂ of the second stock chest 10a₂. Since the stock M₂ of the second stock chest 10a₂ comprises stock that has already previously undergone centrifugal cleaning, said line can be connected directly to the headbox 100 of the paper machine, via its deaeration tank 13a₂ and machine screen 14a₂.

In the embodiment of FIG. 2B, stock M₁, i.e. a pulp fraction, of a first stock chest 10a₁ also comprises a stock composition that requires centrifugal cleaning before it is passed to a headbox of a paper machine. The stock M₁ contains broke coming from the paper machine and it can additionally contain pulp coming from fiber recovery and further mechanical pulp.

Stock M₂ of a second stock chest 10a₂ comprises pulp that has already undergone centrifugal cleaning, such as recycled fiber and/or chemical pulp and/or TMP.

Also in this embodiment of the invention, only the stock M₁ passed from the stock chest 10a₁ is treated in a hydrocyclone plant 20. In the embodiment of the figure, the stock is passed from the stock chest 10a₁ through a line a₁ while pumped by a pump P₁₀ to a mixing device 120, in which the stock is diluted to a centrifugal cleaning consistency with wire water obtained from a line f₄, and the stock M₁ is passed further through a line a₂ to the suction side of a pump P₂₀. The line a₂ on the pressure side of the pump P₂₀ is connected to the hydrocyclone plant 20 to form the feed of its first centrifugal cleaning step 20a₁.

In the embodiment of FIG. 2B, the hydrocyclone plant 20 situated in the short circulation of the paper machine includes centrifugal cleaning steps 20a₁, 20a₂ and 20a₃. An accept line a₃ leads further from the first hydrocyclone, i.e. the centrifugal cleaning step 20a₁ of the hydrocyclone plant 20 into connection with a stock line b₁ of a second stock chest 10a₂.

In the embodiment, wire water from the paper machine is passed to a wire pit 110 through a line d₁, which wire pit 110 in this embodiment is formed by a planar wire pit structure, a so-called flume, which comprises a horizontal flow path for wire water. Said wire pit 110 removes effectively air in bubble form from the wire water, and pre-deaeration of the wire water is accomplished by means of said wire pit type. The wire water is passed from the wire pit 110 through a discharge line d₂ and a pump P₃₀ to a deaeration tank 13a₃, from which there is further a discharge line f₃ leading into connection with the line b₁ of the stock M₂ of the second stock chest 10a₂ via a mixing device 12. The line f₄ leads further from the discharge line f₃ of the deaeration tank 13a₃ into connection with the line a₁ of the stock M₁ of the first stock chest 10a₁ via the mixing device 120. A branch line f₅ leads further from the line f₃ to a pump P₄₀ and further from the pressure side of the pump P₄₀ to a machine screen 14a₃, which conducts the wire water further as accept from the machine screen 14a₃ to a dilution water inlet header J₂ of a headbox 100.

The stock M₂ is passed from the stock chest 10a₂ through a pump P₅₀ along the line b₁ to the mixing device 12 in order to be combined with the stock coming as accept along the line a₃

5

from the hydrocyclone plant 20 and with the dilution water coming along the line f_3 . After that the diluted stock is pumped by means of a headbox feed pump P_{60} through a machine screen 14a₄ to a stock inlet header J_1 of the headbox 100.

As shown in FIG. 3, the hydrocyclone plant 20 includes several centrifugal cleaning steps 20a₁, 20a₂, 20a₃, so that, as shown in the figure, accept from the first step 20a₁ is passed through the line a₃ further into connection with the line b₁ of the stock M₂ of the second chest 10a₂. As shown in FIG. 3, the stock is passed through the line a₁ as a feed to the first centrifugal cleaning step of the hydrocyclone plant 20, i.e. to the hydrocyclone 20a₁. The stock flows along a spiral-shaped path inside the hydrocyclone 20a₁ and heavier particles separate as reject from the bottom of the hydrocyclone and lighter particles rise as accept further through the line a₃ into the line b₁ of the stock M₂ passed from the second stock chest 10a₂. There can be several hydrocyclones 20a₁, 20a₂, 20a₃ . . . and the reject from the first hydrocyclone 20a₁ can be passed further to the second hydrocyclone 20a₂ as its feed and the accept from it in one embodiment can be passed further to the line b₁ of the stock M₂ of the second stock chest 10a₂.

The figure shows a headbox 100. The headbox 100 in accordance with the invention is advantageously a so-called dilution headbox, which means that the dilution water passed to the dilution water inlet header J₂ is passed further across the width of the headbox to different points of the stock passed from the stock inlet header J₁. In this way, dilution makes it possible to regulate the basis weight of the web across the width of the web. The dilution water passed from the dilution water inlet header J₂ is passed to ducts which are provided with dilution water valves, by means of which the supply of dilution water can be regulated as desired across the width of the headbox, thus enabling the basis weight of the web to be regulated to be even across the entire width of the web.

As shown in the figure, the hydrocyclone plant can also include several accept lines, the stock passed through them being conducted into connection with another stock or with stocks passed from other chests. In accordance with the invention, it is also possible to use several stock chests, but in the invention only that stock, such as the broke-containing stock M₁, which shall be treated in the hydrocyclone plant is circulated through the hydrocyclone plant 20. The pulp fraction M₂ which need not be cleaned with hydrocyclones is passed directly to deaeration and, after a machine screen, to the stock inlet header J₁ of the headbox 100. The accept derived from the stock M₁ in the centrifugal cleaning 20 is conducted into connection with said stock.

When the stocks M₁ and M₂ of the chests 10a₁, 10a₂ are referred to in this application, it is also possible to call them a pulp fraction M₁ and a pulp fraction M₂. In this application, the paper machine is understood to mean paper, board and tissue machines.

The broke can be formed of paper broke, which can include trimmings or paper passed to a pulper in connection with web breaks.

The present application refers to lines by which are meant stock lines, pipes, ducts along which stock/wire water is passed.

The invention claimed is:

1. An apparatus for treatment of stock passing to a headbox of a paper machine, comprising:
  - a short circulation of the paper machine;
  - a first stock chest;
  - a hydrocyclone plant forming a part of the short circulation, the hydrocyclone plant connected to the first stock

6

chest by a first stock transporting line, the hydrocyclone plant having an accept outlet line;

a second stock chest having a second stock transporting line;

- 5 a mixing device which is connected to receive stock from the second stock transporting line, the mixing device being connected in stock receiving relation to the accept outlet line so that stock flowing along the accept outlet line is mixed in the mixing device with stock flowing along the second stock transporting line; and wherein a third stock transporting line is connected in stock supplying relation to the headbox.

- 15 2. The apparatus of claim 1, wherein the first stock chest contains stock containing broke.

- 15 3. The apparatus of claim 2, wherein the stock in the first stock chest contains, in addition to broke pulp, recovered fiber pulp, and mechanical pulp.

- 20 4. The apparatus of claim 1, wherein the second stock chest contains stock which has been cleaned by hydrocyclones.

- 20 5. The apparatus of claim 4 wherein the second stock chest stock comprises recycled fiber or chemical pulp.

- 25 6. The apparatus of claim 1, further comprising:
  - a wire pit connected between the first stock chest and the hydrocyclone plant;

- 25 7. The apparatus of claim 6, further comprising:
  - a deaeration tank having a discharge;
  - a wire water supply line connecting the wire pit to the deaeration tank;

- 30 8. The apparatus of claim 7, further comprising:
  - a machine screen connected to receive wire water from the deaeration tank; and

- 30 9. The apparatus of claim 8, further comprising:
  - a dilution water inlet header, in wire water receiving relation to the deaeration tank and in dilution water supplying relation to the head box.

- 35 10. The apparatus of claim 9, further comprising:
  - a first pump connected between the first stock chest and the wire pit;

- 35 11. The apparatus of claim 10, further comprising:
  - a second pump connected between the wire pit and the hydrocyclone plant;

- 40 12. The apparatus of claim 11, further comprising:
  - a third pump connected between the wire pit and the deaeration tank; and

- 40 13. The apparatus of claim 12, further comprising:
  - a fourth pump connected between the deaeration tank discharge and the dilution inlet header.

- 45 14. The apparatus of claim 13, further comprising:
  - a deaeration tank having a discharge line;
  - a pump connected to said deaeration tank discharge line and having a pressure side; and

- 45 15. The apparatus of claim 14, further comprising:
  - a machine screen which is connected to the pressure side of said pump and which is connected to the stock inlet header of the headbox.

- 50 16. The apparatus of claim 15, further comprising:
  - a wire pit connected between the first stock chest and the hydrocyclone plant; and

- 50 17. The apparatus of claim 16, further comprising:
  - a dilution water line from the wire pit which joins the accept outlet line and the second stock transporting line at the mixing device in supplying relation to the third stock transport line.

- 55 18. An apparatus for treatment of stock passing to a headbox of a paper machine, comprising:
  - a short circulation of the paper machine;

- 55 19. The apparatus of claim 18, further comprising:
  - a first stock chest;
  - a hydrocyclone plant forming a part of the short circulation, the hydrocyclone plant connected to the first stock chest by a first stock transporting line, the hydrocyclone plant having an accept outlet line;

a second stock chest having a second stock transporting line, wherein the accept outlet line joins the second stock transporting line to form a third stock transporting line which is connected in stock supplying relation to the headbox, and wherein the accept outlet line joins the second stock transporting line so as to mix stock flowing along the accept outlet line with stock flowing along the second stock transporting line;

a mixing device between the first stock chest and the hydrocyclone, the mixing device forming part of the first stock line;

a second mixing device where the accept outlet line joins the second stock transporting line to form a third stock transport line which is connected in stock supplying relation to the headbox;

a first pump in the first stock line between the first stock chest and the first mixing device; and

a second pump in the first stock line between the first mixing device and the hydrocyclone.

11. The apparatus of claim 10, further comprising a wire water line connected to a source of wire water in the paper machine, the wire water line including a wire pit followed by a deaeration tank, wherein after the deaeration tank the wire water line forms a first branch connected to the first mixing device, a second branch connected to the second mixing device, and a third branch connected to a pump and further to a machine screen and therefrom further to a dilution water inlet header in dilution water supplying relation to the head box.

12. A method for treating stock passed in a short circulation to a headbox of a paper machine comprising the steps of:

passing a first flow of stock to a hydrocyclone plant, and forming an accepts flow of stock;

combining the accepts flow with a second stock flow which has not passed through the hydrocyclone plant in a mixing device to form a combined stock flow; and

passing the combined stock flow to the headbox of the paper machine.

35

13. The method of claim 12, wherein the first flow of stock is supplied from a first stock chest.

14. The method of claim 12, further comprising the step of forming the first flow of stock as a composition containing broke passed from the paper machine.

15. The method of claim 12, further comprising the step of forming the first flow of stock as a composition containing broke passed from the paper machine and pulp coming from fiber recovery or mechanical pulp.

16. The method of claim 13, wherein the second stock flow is taken from a second stock chest into which stock which has been cleaned by a hydrocyclone is passed.

17. The method of claim 12, wherein the second flow of stock contains recycled fiber or chemical pulp.

18. A method for reducing the energy used in a short circulation in a papermaking machine wherein a headbox is supplied stock from an inlet header and wherein the inlet header is supplied with stock from at least a first stock chest of stock which has not passed through a hydrocyclone and a second stock chest of stock which has passed through a hydrocyclone, the method comprising the steps of:

cleaning stock from the first stock chest with a hydrocyclone to form an accepts flow of stock;

mixing the accepts flow of stock with a flow of stock from the second stock chest in a mixing device to form a mixed stock; and

supplying the mixed stock to the inlet header of the headbox.

19. The method of claim 18, further comprising the step of forming the stock in the first stock chest from broke passed from the paper machine.

20. The method of claim 18, further comprising the steps of:

recovering wire water from the papermaking machine; and diluting the stock from the first stock chest with said wire water to less than or equal to 1 percent consistency before cleaning the stock from the first stock chest with the hydrocyclone to form the accepts flow of stock.
